ATTEMPERATOR REGULATING THE TEMPERATURE OF SUPERHEATED VAPOR

Cedric Harold Sparks, London, England, assignor to The Babcock & Wilcox Company, Rockleigh, N. J., a corporation of New Jersey

Application September 25, 1947, Serial No. 776,076
In Great Britain October 2, 1946

3 Claims. (Cl. 122—479)

1

This invention relates to regulation of the temperature of superheated vapor.

Apparatus has been suggested whereby the moisture in saturated steam is regulated for the purpose of controlling the temperature of superheat. It includes a condenser in the form of a steam collector containing a condensing coil for regulating the wetness of the steam, the collector being arranged above a steam and water drum and the bottom of the steam collector being connected with the drum by a number of nipples and being provided in the top thereof with outlets for the wet steam. With such an arrangement the possibility of water hammer is avoided since no slugs of water can pass to the superheater, but part of the condensate is liable to drain back into the steam and water drum. An object of this invention is the provision of condensing means for controlling the temperature of superheat which renders possible the utilization of all the condensate, while avoiding the danger of water hammer. Another object is the provision of an improved method of regulating the temperature of superheated vapor.

The present invention includes a superheat regulator comprising a condenser disposed in the vapor flow path between a source of vapor and a superheater, together with means for withdrawing condensate deposited by the vapor within the condenser and injecting the deposited condensate into the vapor flow path.

The invention also includes the method of regulating the temperature of superheated vapor which comprises passing a stream of vapor from a vapor generator through a superheater, creating a pressure drop at a location in the vapor flow path, condensing vapor from the vapor generator and entraining condensate in the vapor stream by supplying the entrained condensate at least partly at the said location and varying the rate of supply of entrained condensate in order to regulate the temperature of superheat.

The invention will now be described by way of example with reference to the accompanying schematic drawings representing a number of elements of a marine water tube boiler provided with a superheat regulator.

In the drawings:

Fig. 1 of the drawings is an elevation illustrating the apparatus from a side of the boiler; and

Fig. 2 is a front elevation.

Referring to the drawings, in the upper part of a marine boiler a steam and water drum 1 having its longitudinal axis extending from front

2

to rear of the boiler is suitably arranged in a usual manner for the reception of a steam and water mixture from banks of steam generating tubes 1A and 1B suitably arranged below the drum within the boiler casing 2 and heated by gases from a furnace (not shown) also situated within the boiler casing below the drum. Between the banks of the steam generating tubes, superheater tubes (not shown) are arranged for heating by the furnace gases. Within the boiler casing and at one side of the drum an economizer 3 is disposed, arranged for the reception of heat from furnace gases after they have yielded heat to the boiler and superheater tubes.

15 The steam and water drum 1 is provided towards the front end thereof with a drum steam outlet 4 connected to the uppermost part of the drum and communicating with the steam inlet 5 of a condensing chamber 6. The condensing chamber 6 has a length about half that of the steam and water drum 1 and a diameter about one quarter that of the drum and is arranged horizontally at about the level of the top of the steam and water drum.

20 25 The condensing chamber is so formed that one end 7 is closed and at the other end a flange 8 is provided for the securement of a tube plate 9 and associated divided distributing head 10. Extending into the chamber from the tube plate is a bundle of U-shaped condensing tubes indicated at 11, the respective ends of which communicate with an inlet compartment 12 in the divided distributing head to which condensing water may be supplied through a water inlet 13 and with an outlet compartment 14 in the divided distributing head from which condensing water may be withdrawn through a water outlet 15.

30 35 40 45 For the supply of condensing water the water inlet 13 is connected as indicated by 16 with the feed-water inlet header 17 of the economizer and for the withdrawal of condensing water, the water inlet 15 is connected as indicated by 18 with the water outlet header 19 of the economizer. The withdrawal connection 18 is provided with a valve indicated by 20 for the control of the flow of condensing water through the condensing tubes 11.

50 55 The condensing chamber is arranged with its flanged end towards the front of the boiler and its closed end towards the rear of the boiler. The steam inlet 5 of the condensing chamber is provided adjacent the front end thereof, and a steam outlet 21 from the condensing chamber is

provided at the top of the condensing chamber near the rear end thereof. The steam outlet 21 leads steam into one end of a horizontally arranged constrictive steam pipe section 22 from the other end of which steam piping 23 conducts steam downwardly at the rear of the boiler to enter a superheater header 24 into which the ends of the superheater tubes are connected.

The inner wall 22A (or thermal liner) of the constrictive (Venturi) pipe section 22 is so formed that the cross-sectional area of the steam channel therethrough decreases gradually in the manner of a Venturi nozzle from each end of the pipe section to a throat or position of maximum constriction indicated at 29 nearly equidistant from the ends. Connecting with the bottom of the condensing chamber 6 near the rear end thereof is a drain 25 connected to a water pipe 26 arranged to lead condensate water to a water inlet 27 which discharges the condensate into the steam flow through an orifice 28 in the wall of the throat 29.

Nearly midway along its length the condensing chamber 6 is provided with an emergency drain 30 leading from a side of the chamber and connected through a pipe 31 with a drain inlet 32 passing through the wall of the steam and water drum and arranged with its discharge end 33 below a normal water level in the drum.

For the automatic regulation of superheated steam temperature, the flow of feed water through the condensing chamber, in parallel with the water flow through the economizer, is arranged to be automatically regulated by control of the valve 20 in accordance with the steam temperature at the outlet of the superheater. Such automatic regulation may involve a thermostat 40 installed in the superheater outlet header. This thermostat directly actuates the valve 20 through the volumetric changes of a volatile liquid in the thermostat and a pipe connection 41 from the thermostat to the valve 20. During the operation of the boiler, saturated steam flows from the steam and water drum through the steam outlet 4 and steam inlet 5 into the condensing chamber 6, within which steam is condensed in an amount depending upon the rate of flow of water in the condensing tubes 11.

Some of the condensate is carried in suspension by the steam leaving the condensing chamber through the steam outlet 21, but a proportion of the condensate falls to the bottom of the condensing chamber from which it is withdrawn by the drain 25 and, under the influence of reduced steam pressure at the throat 29 of the Venturi nozzle within the pipe section 22, is conducted by the pipe 26 and inlet 27 and injected through the orifice 28 into the steam flow within the pipe section 22. The condensate enters the steam channel as a spray and is entrained by the steam. The steam pressure lost at the throat 29 is substantially regained in the steam during its flow to the outlet end of the pipe section 22.

Control of the valve 20 and therefore of the rate of flow of water in the condensing tubes 11 operates to vary the wetness of the steam led to the superheater and the temperature of superheat is accordingly regulated. Since the condensate formed at any moment is quickly carried away by the steam, an effective control of the temperature of superheat is obtained and since condensate is continuously drained from the con-

densing chamber, the danger of water hammer is avoided.

Should the quantity of water in the condensing chamber reach an abnormal value such as to cause a sufficiently high water level at the position of the emergency drain 30, water will flow from the condensing chamber through the pipe 31 and drain inlet 32 and will be discharged through the discharge end 33 into the water in the steam and water drum.

What is claimed is:

1. In a vapor generator, a vapor and liquid drum, a superheater, means including a conduit providing for the flow of vapor from the drum to the superheater, a vapor condenser disposed in the vapor flow path from the drum to the superheater, means supplying a controlled amount of cooling fluid to the condenser, said conduit having a venturi therein, the venturi normally creating a pressure drop at one position in said conduit and a tubular connection between the condensate space of the condenser and the position of said pressure drop at the throat of the venturi whereby condensate flows to the venturi and is mixed with the vapor passing through the venturi.

2. In a vapor generator, a vapor and liquid drum, a superheater including an inlet header, means including a conduit providing for the flow of vapor from the drum to the superheater inlet header, a vapor condenser disposed in the vapor flow path from the drum to the superheater header, means supplying a controlled amount of cooling fluid to the condenser, said conduit having a venturi normally creating a pressure drop at a position in the conduit, and a tubular connection between the condensate space of the condenser and the position of said pressure drop at the throat of the venturi whereby condensate flows to the venturi and is mixed with the vapor passing through the venturi.

3. In a vapor generator, a vapor and liquid drum, a superheater including an inlet header, means including a single conduit providing for the flow of vapor from the drum to the superheater inlet header, a vapor condenser disposed in the vapor flow path from the drum to the superheater, means supplying a controlled amount of cooling fluid to the condenser, said conduit having a venturi normally creating a pressure drop at a position in the conduit, a tubular connection between the condensate space of the condenser and the position of said pressure drop at the throat of the venturi whereby condensate flows to the venturi and is mixed with the vapor passing through the venturi, and means limiting the level of the condensate in the condenser.
